UNITED STATES PATENT OFFICE

156,589

CASING FOR HEATER OR SIMILAR ARTICLE

Arthur F. Wedderspoon, Chicago, Ill., assignor
to Cole Hot Blast Mfg. Co., Chicago, Ill., a cor-
poration of Illinois

Application January 16, 1948, Serial No. 143,834

Term of patent 7 years

(Cl. D81—19)

To all whom it may concern:

Be it known that I, Arthur F. Wedderspoon, a citizen of the United States and a resident of the city of Chicago, in the county of Cook and State of Illinois, have invented a new, original, and ornamental Design for a Casing for Heater or Similar Article, of which the following is a specification, reference being had to the accompanying drawing, forming a part thereof.

On the drawing, the figure is a perspective view of the casing for a heater or similar article, showing my new design.

The other side of the casing, not shown, is substantially like the side shown.

I claim:

The ornamental design for a casing for heater or similar article, as shown and described.

ARTHUR F. WEDDERSPON.
